METHOD OF AND MEANS FOR BURNING LIQUID FUEL.

1,284,182.

Specification of Letters Patent.

Patented Nov. 5, 1918.

Application filed December 28, 1917. Serial No. 209,210.

To all whom it may concern:

Be it known that I, ABNER DOBLE, a citizen of the United States of America, and resident of Detroit, Wayne county, Michigan, have invented a certain new and useful Improvement in Methods of and Means for Burning Liquid Fuel, of which the following is a specification.

My invention relates to the art of burning 10 heavy liquid hydrocarbons in connection with the production of steam, especially in that class of steam generators particularly designed for motor-driven vehicles such as steam-driven automobiles, wherein the space 15 available for a generator is extremely limited, and excessive weight must be avoided, and yet the power plant must have a capacity for the rapid economical production of a large volume of high pressure, high temperature steam entirely disproportionate to 20 the size of power plants generally.

The rapid production of a large volume of high pressure steam as required by a steam-driven automobile, of course, necessitates the consumption of a proportionately 25 large volume of fuel, and in connection with an automobile power plant, differing in this respect from any other power plant, this consumption of fuel in large volume must be 30 accomplished without giving off any smoke.

The higher the degree of the fire-box 35 temperature attainable, the smaller need be the boiler or steam generating unit, and as the degree of fire-box temperature is directly proportionate to the quantity of fuel capable 40 of being consumed with complete combustion, the effectiveness of any fuel burning device is measured by its fuel consuming capacity.

It is well known that if the flame of 45 burning fuel in the fire-box of a steam generator be permitted to contact a surface, the temperature of which is considerably lower than that of the flame of the burning fuel, soot and smoke will result. This comparatively 50 colder surface may be the shell of the fire-tube boiler or the tubes of a water-tube boiler. It is further well known that if the fuel is not mixed with sufficient air to insure 55 its complete combustion, smoke and soot will result even though the flame is not permitted to contact with relatively colder surfaces. When heavy hydrocarbon oil fuel is used in a steam generator under forced con-

ditions by being projected under pressure into the combustion chamber, a voluminous flame of considerable length develops, and in connection with a fire-box or combustion chamber of huge proportions, this lengthy voluminous flame will have ample space 60 within which to burn without contacting with the relatively cold surfaces to the point of rendering complete combustion impossible. In those classes of steam generating plants wherein the size of the combustion 65 chamber, and wherein the formation of soot and smoke are of no particular moment, the voluminous flame resulting from the burning of the fuel without first transforming it into a gas, can be accomplished by providing 70 a sufficiently large combustion chamber. In a steam generating plant of a size which is to be installed, for instance, under the hood of a modern automobile without materially disturbing the conventional lines and dimensions of the hood, the head room is so limited 75 that after utilizing that portion of the available space necessary for the evaporating section of the generator, very little space remains for the fire-box or combustion chamber. In fact, this chamber in practice will not be over twenty inches across, and about eight inches deep. A chamber of any considerable depth could not be employed.

In steam generating plants heretofore 80 employed for the purpose of generating steam to propel an automobile and the like, that type of generating apparatus has been employed in which a gas burner is used, and this necessitates the preliminary transformation 85 of the liquid fuel into a gaseous fuel which produces at the burner, a flame of extremely small vertical dimension and of a considerable degree of intensity. While this type of apparatus is peculiarly adapted for 90 the generation of steam in an automobile power plant because of its adaptability to the limited and circumscribed area of the combustion chamber, this preliminary transformation 95 of the fuel, to render it capable of combustion in a restricted combustion chamber, is manifestly an objectionable time-consuming operation and the character of the burners necessarily used not only renders it troublesome and dangerous, but its 100 limitations in fuel consumption and consequent fire-box temperature renders it undesirable for use in a small steam generating unit.

The object of my invention is to eliminate 110

the burner and the consequent necessary transformation of the liquid fuel into a gaseous fuel, and to burn non-volatile liquid fuel in sufficient volume within the limits 5 of the necessarily restricted combustion chamber, without smoke and soot, and without bringing about heat insulation of the surfaces of the generating apparatus through soot deposits which tend to materially reduce 10 the generating capacity of such apparatus.

The problem presented, when the liquid fuel is introduced and burned without preliminary vaporization is to not only directly 15 and completely burn large quantities of liquid fuel, but to burn such large quantities in an exceedingly small space without permitting the flame to contact with the relatively colder surfaces of the steam generator. I have solved this problem by my invention, which contemplates the introduction, into a shallow closed combustion chamber, of relatively large quantities of a mixture of atomized liquid fuel and all of the 20 air necessary to support complete combustion, and confining the flame, by virtue of various forces applied thereto, within the limited space of said combustion chamber until the combustion of the fuel is complete.

30 My invention comprehends both the method for accomplishing this result, and the apparatus by which the method is carried into effect.

In the accompanying drawings—
35 Figure 1 is a vertical section of a portion of a steam generator showing my improved liquid fuel combustion apparatus in position relative to the water tubes or evaporating devices.

40 Fig. 2 is a top plan view on the line 2—2 of Fig. 1.

Fig. 3 is a plan view similar to Fig. 2, but of a modified form of combustion chamber.

Fig. 4 is a vertical section on line 4—4 of 45 Fig. 3.

In Fig. 1, the water tubes 1, together with the heat retaining casing 2, are representative of a steam generator of that type having a capacity for a large volume of steam 50 entirely disproportionate to its physical dimensions, such, for instance, as is employed in steam-driven automobiles and the like.

Immediately beneath this generator is a combustion chamber A which is open at its 55 top side only, so that the radiant heat of the completely consumed fuel rises directly into the generator casing. This combustion chamber is formed by a bowl-shaped member of suitable metal or refractory material 3, 60 and is surrounded by a sheet metal casing 4 for purposes of protection. In plan section, the chamber is, in general, rectangular to conform to a steam generator of rectangular conformation, but in Fig. 3 the chamber is 65 circular to conform to a steam generator of

the circular type. In either construction the bottom wall 5 is preferably perfectly flat and horizontal, and the side walls 6 are vertical and perpendicular to the bottom wall. A baffle flange 6^a surrounds the upper edge of 70 the combustion chamber member and extends abruptly inwardly and horizontally at right angles to the side walls. This disposes the inner surface of the flange practically parallel with the surface of the bottom wall. In 75 the rectangular construction, the corners 6^b, formed by the angles between the contiguous side walls, are curved or rounded so as to offer less resistance to the horizontal movement of the flame, and thus act to more 80 gradually turn the flame back upon itself in a horizontal direction. In the circular form of Fig. 3, the vertical walls of the combustion chamber follow a constant curve and accomplish the same result. It will be observed, however, that the combustion chamber is exceedingly shallow in vertical dimension, and that the flame of combustion 85 must be restricted to substantially this vertical dimension in order to prevent its contacting with the relatively colder surfaces 90 of the steam generator tubes which are immediately above the combustion chamber.

Extending vertically from the floor or bottom wall to the underside of the baffle flange 6, along the side wall of the combustion chamber, is a triangular flame dividing and deflecting member 9 which may be integral with the wall and flange. The angling sides 9^a of this divider are concaved 95 or curved, describing an arc of approximately the same radius as the adjacent corners of the chamber, whereby these curved sides will gradually turn the flame horizontally back upon itself.

100 The fuel is introduced into the combustion chamber at one side thereof by means of a mixture-forming and propelling mechanism. The structure shown in the drawings comprises in general a pair of mixture forming Venturi tubes 10 which extend through the side wall of and into the combustion chamber and which have tubular passages 11, the axes of which are disposed substantially horizontally and pointed directly toward the flame divider 9 on the opposite side wall of the combustion chamber. The outer ends of these tubes are connected to the outlet of an air blower 12 having a rotary blade wheel 13 and of a type 110 which is capable of delivering large quantities of air at low pressure. In the throats of the tubular passages 11 are liquid-fuel nozzles 14 connected with any suitable source of liquid fuel supply and subjecting 115 the liquid fuel to the atomizing action of the air which is projected through the Venturi tubes by the blower. I illustrate two atomizing and mixture forming Venturi tubes 120 because I find in practice that the large vol- 125

time of fuel and air necessary to meet the demands of the generator can be projected into the combustion chamber to better advantage. The fuel, being thus atomized, is 5 projected into the combustion chamber in the form of a spray properly mixed with the air which supports combustion. The combustion chamber is closed against the entrance of air in all respects except that 10 which is introduced through the mixture forming mechanism. On account of the relatively large quantity of fuel which has to be burned, a relatively large amount of air must be introduced into the combustion 15 chamber in order to bring about the complete combustion of the fuel. It will be observed, however, that not only all of the fuel, but all of the air for complete combustion of the fuel, is introduced into the 20 chamber through this mixture forming mechanism. I introduce all of the air and fuel in this manner, because I am enabled to impart to the entire body of mixture that degree of force which is necessary for the 25 purpose of confining the flame within the restricted combustion chamber, and because I have found in actual practice that if the natural draft through openings in the combustion chamber is employed, it is impossible 30 to introduce a sufficient volume of air to completely consume the large volume of fuel, and also because it becomes impossible to create and maintain that degree of pressure and force, within the fire-box, necessary 35 to give to the flaming fuel the desired shape and direction. Now, since the process of combustion necessarily occupies some considerable period of time in order to completely consume the fuel, it is manifest that 40 a flame considerably longer than the length of the combustion chamber is necessarily developed, but by projecting the flame directly across the combustion chamber in a horizontal direction to the opposite side wall thereof, 45 and then turning the flame back in the same horizontal direction upon itself by the reactive forces established by the walls and baffles of the combustion chamber, the flame will be given a vortex formation, and will 50 remain in the combustion chamber until the length of the flame is expended and combustion completed. To accomplish this result, I project or propel the mixture, by means of a blower, with that degree of force 55 which will overcome the natural tendency of the flame to rise, and I utilize the reactive force of the side walls and instanding flange to continuously turn this horizontal projecting flame back upon itself until combustion 60 is complete. Since the vertical baffle or flame divider is directly in the path of the stream of flame from the mixture-forming mechanism, that flame is divided thereby and turned laterally in two directions, with the 65 result that a double vortex of horizontally

moving flame is produced. Each of the divisions of flame are projected along the walls of the chamber and at the curved corners is repeatedly turned back into the vortex. Any further or other tendency of the 70 flame, if any there be, to rise out of the combustion chamber is offset by the reactive force of the continuous baffle flange surrounding the upper edge of said combustion chamber.

75

What I claim as my invention is:

1. In a fuel oil combustion chamber, a horizontal floor, vertical side walls, a substantially continuous baffle extending inwardly from the upper edge of said side walls substantially parallel with the floor and forming a substantially central outlet for the hot gases and products of combustion, a device on one side of the chamber for projecting flaming fuel in a horizontal plane 80 into said chamber, and a vertically positioned deflector, adjacent the opposite side, against which the flaming fuel is projected and by which it is deflected in two paths each in a horizontal plane, whereby to confine the flame within the combustion chamber.

2. In a fuel oil combustion chamber, having a substantially flat floor and side walls extending vertically at right angles thereto, a substantially continuous baffle extending abruptly inward from the upper edge of said side walls substantially parallel with the floor, a flame deflector adjacent the side wall extending from the said baffle to the 100 floor, and a device on the side opposite from said deflector adapted to project the burning fuel thereagainst.

3. In a fuel oil burning device, the combination of a combustion chamber closed at the bottom and open at the top, a substantially continuous flange extending abruptly inward at the upper edge thereof forming a narrow ledge or baffle, an atomizer for projecting burning fuel into said chamber 105 through one side wall thereof, and a vertical flame dividing deflector adjacent the side wall opposite the atomizer.

4. In a fuel oil burning device, the combination of a combustion chamber closed at the bottom and open at the top, a substantially continuous flange extending abruptly inward at the upper edge thereof forming a narrow ledge or baffle, an atomizer for projecting burning fuel into said chamber 110 through the side wall thereof, a vertical flame dividing deflector adjacent the side wall opposite the atomizer and extending from said baffle to said floor.

5. In a fuel oil burning device, the combination of a combustion chamber closed at the bottom and open at the top, a substantially continuous flange extending abruptly inward at the upper edge thereof forming a narrow ledge or baffle, an atomizer for 115

125

130

projecting burning fuel into said chamber through a side wall thereof, a vertical flame dividing deflector adjacent the side wall opposite the atomizer with its edge 5 extending toward the atomizer and extending from said baffle to said floor.

6. In a fuel oil burning device, the combination of a combustion chamber having a substantially flat bottom and vertical side 10 walls, means for projecting a flaming combustible into said chamber through a side wall, means associated with the side wall opposite said flame projecting means causing a vortex formation of said flaming combustible traveling in a horizontal plane parallel to the bottom of said chamber, and a substantially continuous narrow ledge extending abruptly inward from the upper edge of said combustion chamber forming 15 a baffle, whereby said flame is confined within the vertical limits of said chamber.

7. In a fuel oil burning device, the combination of a fire-pot forming a flame chamber having a substantially flat floor, means 20 for projecting a flame combustible into said chamber in a horizontal plane parallel with the floor thereof, means for causing the stream of flaming combustible to divide into vortices traveling in a horizontal plane parallel to the floor of said chamber, whereby 25 to confine the combustion of the fuel substantially within the vertical limits thereof.

8. The method herein described of burning 30 atomized liquid hydrocarbon fuel in a confined shallow combustion chamber, consisting in injecting in a substantially horizontal plane all the combustion-supplying air and the fuel in an atomized condition into said chamber, swirling the burning 35 mixture within the chamber with sufficient force to confine the mixture in said substantially horizontal plane within the chamber until flaming thereof ceases so that only the products of combustion and radiant heat 40 will escape from the chamber.

9. The method of burning fuel which consists in projecting a stream of sprayed liquid fuel and air, in sufficient proportion to support complete combustion, with such force 45

as to compel said stream to remain in a 50 horizontal plane, and doubling the stream upon itself in a horizontal plane and confining it in said plane until combustion is complete.

10. The method of burning heavy liquid 55 hydrocarbons which consists in finely dividing the liquid and mixing therewith a proportion of air sufficient to support complete combustion, propelling said mixture with that force which is necessary to compel its flame, if unconfined, to remain in substantially a given plane, for substantially its 60 entire length, constantly turning said flame upon itself in the same said plane and confining it against diversion from that plane 65 until combustion is complete.

11. The method of burning relatively 70 large quantities of liquid fuel in a relatively small space, which consists in forming a mixture of finely divided liquid fuel 75 and all of the air necessary to completely burn said fuel, constantly propelling a stream of said mixture horizontally with that degree of force which is necessary to compel the flame to remain, if unconfined, in a horizontal plane for substantially its entire length, repeatedly turning the flame back upon itself in said horizontal plane until combustion is complete, and limiting the vertical dimension of the flame by confining it against vertical expansion while moving horizontally.

12. The method herein described of burning 80 atomized liquid hydrocarbon fuel in a confined shallow combustion chamber, consisting in projecting in a substantially horizontal plane all the combustion-supplying air and fuel in an atomized condition into said chamber, swirling the burning mixture 85 within the chamber with sufficient force to confine the mixture in a mass having well defined upper and lower horizontal surfaces until combustion is complete, so that only the products of combustion and radiant heat 90 will escape from the chamber.

Signed by me at Detroit, Michigan, this 95
26th day of December, 1917.

ABNER DOBLE.
